UNITED STATES PATENT OFFICE

ORVILLE H. ENSIGN, OF PASADENA, CALIFORNIA, ASSIGNOR TO ENSIGN CARBURETOR COMPANY, OF LOS ANGELES, CALIFORNIA, A CORPORATION OF CALIFORNIA

CARBURETOR

Application filed June 11, 1924. Serial No. 719,297.

My invention relates to that class of carburetors for internal combustion engines wherein a depression caused by the main air stream is communicated through a fuel passage to the fuel for the purpose of proportioning the flow of fuel to air.

It is well known that in carburetors of this type, a small air bleed opening into said fuel passage will materially change the proportion of fuel to air.

An object of this invention is to automatically apply such an air bleed to the fuel passage to thin the mixture, and to automatically limit the application of such air bleed to such temperatures of the mixture that will allow the successful operation of the engine with the thin mixtures resulting from the application of this air bleed.

It is also well known that when the engine is cold it is necessary that the supply of air to the carburetor be decreased, or the supply of gasoline correspondingly increased, unless the mixture is supplied to the engine in a state of high vaporization; and that in such cases even though the engine is cold, it will operate satisfactorily if supplied with a thin highly vaporized heated mixture.

An object of this invention is to provide a carburetor with novel automatic means whereby the operation of an economizer air bleed on a carburetor or fuel converter is limited or controlled by the temperature of the mixture passing through such carburetor, so that such air bleed can be made practicable.

Another object is to provide novel automatic means whereby maximum economy and operation is obtained through the ordinary driving range of an automobile, without the operator having to specially adjust the mixture by a choke or other means during the warming up period.

A further object is to provide means to automatically modify the mixture of a self-heating type carburetor for purposes of economy and to limit such modification to the temperature of the mixture passing through the carburetor that makes practical such economy.

The invention comprises the parts and combination and arrangement of parts herein-after more specifically referred to.

Although I have shown my invention as applied to a carburetor known as a fuel converter, the broad principles of this invention may be applied to any standard form of carburetor.

Other objects, advantages and features of invention may appear from the accompanying drawing, the subjoined detail description and the appended claims.

The accompanying drawing illustrates the invention as applied to a fuel converter type of carburetor.

Figure 1 is a fragmental vertical section on irregular line $\alpha_1-\alpha_1$, Fig. 2, through a carburetor constructed in accordance with this invention, and showing the throttle valve in position for idling and the fuel at rest.

Fig. 2 is a condensed fragmental plan view of the carburetor shown in Fig. 1. Parts are broken away to contract the view, and the throttle valve is in full load position to show parts underneath.

Fig. 3 is a vertical detail in section on line $\alpha_3-\alpha_3$, Fig. 2.

Fig. 4 is a fragmental horizontal section on line $\alpha_4-\alpha_4$, Fig. 3 showing the thermostat valve passage partially open under influence of the heated mixture passing the throttle.

The invention may be carried out with various types and forms of carburetors or mixing valves or devices that will properly proportion the fuel and air for the mixture, and is shown as attached to a carburetor in which a portion of the mixture, the fuel and the air is diverted from a mixture passage to a place where combustion is effected to heat the mixture.

The proportioning and mixing chamber 1 receives its air through the air inlet 2, and its liquid fuel through the fuel jet 3 in a well known manner, and produces a mixture of more or less broken-up fuel and air, which mixture is emitted from said mixing chamber into an inclined mixture passage 4 that has an abrupt upward bend at 5 and there communicates with an upwardly directed limb or riser 6 to the throttle cham-

ber 7, which is separated by the throttle 8 on shaft 8' from the diffusion chamber 9.

The liquid fuel and air are supplied to the mixture chamber 1 by suitable proportioning means, as the constant level fuel supply chamber 10 and the air inlet 2, operating in conjunction with each other and the engine suction, whereby liquid fuel and air are supplied in proportions to produce an explosive mixture; so that the final product issuing from the diffusion chamber 9 is adapted for complete combustion without the addition of either air or fuel.

Liquid fuel is supplied to the fuel chamber 10 through the usual fuel connections at 11 controlled by valve 12, the float 13 in the supply chamber cooperating to maintain the fuel in said chamber at a constant level 14, and the fuel being delivered from the supply chamber 10 through the fuel orifice 15 into the fuel passage 16 from which it is delivered to the main air stream of the carburetor through the fuel jet 3.

The combustion chamber 17 is suitably supplied with fuel and air from the mixture passage 4 in any well known way, as through the fuel passage 18, 18', and the air supply pipes 19, 19'; the mixture in the combustion chamber 17 being fired by the usual spark plug 20 and the hot gases withdrawn from the combustion chamber and returned to the mixture at the diffusion chamber 9 through the gas flue 21, in the usual way with the type of carburetor shown.

This invention resides in automatically opening and closing, at predetermined manifold depressions, an air bleed comprising a passage 22 that is open at one end to the atmosphere as at 22' and is connected at its other end to the enlargement as at 23, of the fuel passage 16; and in also automatically controlling the operation or application of said air bleed by thermostatic means A.

The passage 22 is normally closed by a gravity check valve 24 and admits air to the fuel passage 16, and operates in the same manner as set forth in my co-pending application, filed May 3, 1924, Serial No. 711,913, except as modified or controlled by said thermostatic means A.

The thermostatic means is preferably mounted in a bore 25 formed in a boss 26 extending from the side walls of the riser 6; and comprises a thermostatic member such as a strip or ribbon of laminated thermostatic metal 27 wound in a helix as shown in Figs. 1 and 3. One end of the ribbon 27 is fixed in the bore 25 by securing said end by a pin 28 to a reduced end of a plug 29 which is fixed in the bore by a pin 30 that passes through such plug and the boss 26. A valve plug 31 having an opening 32 is fixed to the other end of said ribbon 27 by a pin 33. A seal 34 is driven into the top of the bore

25 and seals the thermostatic means therein so that it cannot be tampered with.

The valve plug 31 is adapted to open and close a passage 35 that is open at one end 35' to the diffusion chamber 9 above the throttle, and is connected at its other end through a tube 36 to one side of a spring depressed piston 37 which normally closes the air bleed passage 22.

The fuel at the bottom of passage 4 which is not used in the combustion chamber is diverted into the gas flue by way of the ports c and c', the annulus d and the flue ports e. The throttle 8 is perforated by the small hole b to maintain draft in the gas flue 21 during idling of the engine.

In operation the carburetor being operably connected to the manifold of an engine, not shown, the suction of the engine will draw in air at the air inlet 2 of the mixing chamber 1, and the flow of air through such chamber will cause, about the jets 3 a depression which will be communicated through the fuel passage 16 to its enlargement 23 where such depression acts upon the fuel in the fuel passage to cause fuel to flow through the fuel orifice 15, fuel passage 16 through the fuel jets 3 thus putting the carburetor in normal operation.

Fuel will then be more or less vaporized or atomized by the whirling motion of the air in the mixing chamber 1 and the mixture will issue therefrom to the mixture passage 4 flowing around the bend 5 through the limb 6 past the throttle 8 to the diffusion chamber 9 and thence to the manifold.

With the present-day gasoline only a portion of the fuel becomes vaporized by atomization or otherwise without heat, therefore much of the fuel falls to the floor of the passage 4.

Combustion in chamber 17 heats the carburetor and the mixture. The fuel for supplying this combustion will be taken from the fuel on the floor of the mixture passage 4 and will flow through the passage 18 and issue from the nozzle 18' into the combustion chamber 17. Air will flow through the passage 19 and mingle with the fuel issuing from 18'. Air will also flow through the passage 19' and over the top of the distributor a issuing thence into the combustion chamber thereby sustaining combustion.

Ignition occurs at the spark plug electrode 20 from a suitable ignition circuit not shown. The products of combustion from the combustion chamber 17 are withdrawn through the gas flue 21 to the diffusion chamber 9; and when the throttle is closed the flow is largely through the small hole b in the throttle 8 and when the throttle is open as shown in Fig. 2, the flow is direct to the diffusion chamber 9 where the hot gases mingle with the mixture which has passed in the normal way.

After operating for a short time, the floor of the passage 4 and the portion of the passage around the bend 5 and through the limb 6 become heated so that vaporization of much of the fuel takes place by contact with the walls of the passage, and the heat from the combustion chamber is conducted by the passage walls to the walls of the throttle chamber 7 and the diffusion chamber 9 and heats the same materially.

Further heat is communicated to the upper end of passage 4 by the mixture coming in contact with the hot lower portions of the mixture passage 4 and the gas flue 21.

But at all times there are portions of the heavy ends of the fuel, which do not vaporize at the temperatures available by the means above described, and these portions will enter the ports c , c' and pass through the annulus d and the holes e in the gas flue and thus be delivered directly into the red hot products of combustion leaving the combustion chamber and are fully vaporized within the gas flue 21.

This operation reaches this stage very shortly after starting the cold carburetor, enabling the carburetor without the operation of the economizer bleed to go immediately into full, flexible operation of engine even in very cold weather.

In the present invention, the economizer valve 37 is held closed on its seat by the tension of the spring 38 when the engine is at rest, and the spring 38 is sufficiently powerful to close the economizer valve 37 at an engine speed corresponding to a predetermined controlled road speed on a level road at say about 40 miles per hour.

At all road controlled speeds below the predetermined speed this economizer valve will be open. At all speeds above, it will be closed; but at any controlled speed below the limit of about forty miles an hour upon opening the throttle to accelerate the car, the economizer valve instantly closes and will remain closed until the new controlled speed is attained when such valve will open again and allow air to enter the economizer air bleed 22 to the enlargement 23 of the fuel passage 16, thereby materially thinning the mixture in the carburetor.

The depression on the engine side of the throttle is sufficient at all of the above-mentioned controlled engine speeds to draw the piston operated economizer valve 37 away from its seat and said depression is applied through the tube 36 and the valve 31.

The thermostat unit A, which operates to rotate the valve 31 within its bore, is normally adjusted to begin to open the valve 31 at a temperature that will allow flexible operation of the car with the bleed 22 open. Thus in starting out with a cold motor and cold carburetor the air bleed 22 remains closed, and normal full power mixture is maintained

until such time as the temperature of the mixture becomes high enough to allow the car to operate successfully with the air bleed open when the valve 31 is opened thereby allowing operation of the economizer air valve 37.

The normal operating characteristics of the carburetor with the combustion chamber is such as to give a higher mixture temperature at the throttle when the motor is idling; at which time the motor is at its lowest operating temperature, and at the same time the carburetor is raising the temperature of the mixture for applying the load without losing flexibility.

On the contrary when the motor is operated at full load and at wide open throttle, the mixture temperature issuing at the throttle is at its lowest, thus giving full power with a cooler mixture and warmer engine, at which time if the heat were derived from the engine the power would be restricted. It is therefore seen that this thermostat allows operation of the air bleed 22 to thin or enrich the mixture without regard to the engine temperature; operating solely by the mixture temperature from heat generated within the carburetor itself.

Should the carburetor be supplied with hot air from a stove or the exhaust pipe or heated by other means from the engine, the economizer will only operate to thin the mixture when the mixture temperature is such as to make it practical to use such thin mixture.

I claim:

1. In combination with a carburetor, an economizer air bleed valve connected and adapted to be operated by predetermined manifold depression for controlling the admission of air into the fuel passage of the carburetor; a thermostat controlled valve positioned to be influenced by the temperature of the mixture to operatively connect and disconnect from the manifold the economizer valve at predetermined mixture temperatures.

2. In combination with a carburetor, an economizer air bleed valve connected to and adapted to be operated by predetermined manifold depressions for controlling the admission of air into the fuel passage of the carburetor; a thermostat controlled valve positioned to be influenced by the temperature of the carburetor to operatively connect and disconnect from the manifold the economizer valve at a predetermined temperature of the carburetor.

3. A carburetor provided with an economizer air bleed valve operably connected to the engine side of the throttle by a passage for controlling admission of air into the fuel passage of the carburetor; a valve to open and close said passage; and means influenced

by the mixture temperature to open and close said passage valve.

4. A carburetor provided with an economizer air bleed valve operably connected to the engine side of the throttle by a passage for controlling admission of air into the fuel passage of the carburetor; a valve to open and close said passage; and thermostatic means to open and close said passage valve.

10 5. A carburetor provided with a fuel supply chamber and a fuel passage from said supply chamber to the main air stream; an air passage connected to said fuel passage; valve means operable by manifold depressions controlling the entrance of air into said fuel passage through said air passage; and thermostatic means to allow operation of said manifold depression operated means only at predetermined temperatures.

20 6. A carburetor adapted to be attached to an engine manifold having a fuel supply chamber and a fuel passage from said supply chamber to the main air stream provided with an enlargement; an air passage connected to the enlargement of said fuel passage; means operable by predetermined manifold depressions controlling the entrance of air into said enlargement; and a thermostatic device positioned to be operably influenced by predetermined mixture temperatures to further control the operation of said means.

7. A carburetor provided with a fuel supply chamber and a fuel passage from said supply chamber to the main air stream; an air passage connected to said fuel passage; a gravity check valve controlling said air passage; valve means operable by manifold depressions controlling the entrance of air into said fuel passage; and thermostatic means to allow operation of said manifold depression operated means only at predetermined temperatures.

8. A carburetor adapted to be attached to a throttle controlled engine manifold, said carburetor having a supply chamber and a fuel passage from said supply chamber to the main air stream; an air passage connected to said fuel passage; means operable by manifold depressions controlling the entrance of air into said passage comprising a piston and a passage connecting one side of said piston to the manifold above the throttle; and a thermostatic device comprising a thermostatic member non-rotatably mounted at one end and having a rotatable valve plug mounted in its other end; said valve plug having an opening adapted to open and close at a predetermined temperature the passage connecting one side of the piston to the manifold.

9. A carburetor provided with a fuel supply chamber and a fuel passage from said supply chamber to the main air stream; an air passage connected to said fuel passage; a

spring depressed piston normally closing said air passage; a passage connecting one side of said piston to the air stream above the throttle of the carburetor; and means to automatically open and close the passage from the piston to the engine side of the throttle.

10. A carburetor provided with a fuel passage; a valve controlled economizer air bleed opening into said fuel passage; means operable by manifold depressions to open said valve; and automatic means to prevent operation of said valve at predetermined temperatures.

In testimony whereof, I have hereunto set my hand at Los Angeles, California, this 4th day of June, 1924.

ORVILLE H. ENSIGN.
